UNITED STATES PATENT OFFICE.

HARRY E. DILL, OF CLARINDA, IOWA, ASSIGNOR TO CLARINDA POULTRY,
BUTTER & EGG CO., OF CLARINDA, IOWA, A CORPORATION OF IOWA.

MILK-CAN.

No. 800,085.

Specification of Letters Patent.

Patented Sept. 19, 1905.

Application filed March 30, 1905. Serial No. 252,858.

To all whom it may concern:

Be it known that I, HARRY E. DILL, a citizen of the United States of America, residing at Clarinda, in the county of Page and State 5 of Iowa, have invented certain new and useful Improvements in Milk-Cans, of which the following is such a full, clear, and exact description as will enable others skilled in the art to which it appertains to make and use 10 the same, reference being had to the accompanying drawings, forming a part hereof.

This invention relates to improvements in milk-cans, and has special reference to cans for transporting milk and cream to creameries.

15 The object of the invention is to provide a can by the use of which sample-jars may be carried in a compact form without liability to breakage and in a handy and cleanly manner.

20 Large creameries obtain their supply from a number of patrons at scattered points, and these patrons deliver their cream to station agents, whose duty it is to weigh the cream and take out a sample to be tested at the central plant to determine the percentage of butter-fat in the cream. Unless a sample is taken and shipped separately from the main quantity of the cream it is necessary to ship many cans which would be only partly filled, and 25 this is a great expense, as the transportation charges on a partly-filled can are the same as on one which is full. To overcome this waste, sample-jars have heretofore been shipped in a long tube which has been placed inside the 30 can containing the cream. When the can is received at the central plant, this tube must be removed and is found always covered with cream which must be removed or washed from the tube before the jars are taken from the 35 tube to test the samples. This method is obviously unclean and unhandy and causes a great loss of cream. It has also heretofore been a practice to place the sample-jars in a small box which was tied or otherwise fastened to the can; but this method has been 40 very objectionable, as it was unhandy for the railway or other employees who had to handle the cans. Furthermore, frequent losses of the jars occurred through breakage due to 45 overturning of the can and other accidents.

50 All these objections are avoided in the present invention, which consists in utilizing the lid of the can as a carrier and sealing the cover to the body of the can in such manner that

the jars are held firmly in place, so that they 55 cannot break and will be entirely out of contact with the cream in the can.

In the annexed drawings, Figure 1 is a vertical diametrical section of a milk-can embodying the invention. Fig. 2 is a horizontal 60 section on the line $\alpha\alpha$ of Fig. 1, and Fig. 3 is a plan view.

The can A is of the usual or any preferred form and of the usual capacity. The lid B is formed with a hollow depending portion C, 65 fitting within the cylindrical neck of the can, and within this depending portion above the bottom of the same is a horizontal partition or diaphragm D, having a plurality of openings E. On the inner wall of the lid is provided a loop or keeper F, and at a point diametrically opposite the said keeper the lid is provided with a small opening or perforation G, which is adapted to register with a similar opening or perforation in the neck of the can 70 near the upper edge of the same. The cover H is provided with a small tongue, lug, or projection I, which engages the keeper F, and diametrically opposite the same is a fastening plate or lip J, having a perforation or small 75 opening K, adapted to register with the opening G in the lid. A wire L is inserted through the several registered openings and has its ends fastened by a seal M, as shown. The sample-jars N are fitted in the openings in the 80 horizontal partition and rest on the bottom of the lid, while the cover rests upon the tops of the jars. It will thus be seen that a large number of sample-jars may be shipped without taking up any more room than is now occupied without shipping the jars, and, furthermore, the cans can be filled, so that there will be no paying of charges on partly-filled 85 cans. The jars do not touch the cream in the can, so that they reach the central plant in a 90 clean condition and there is no inconvenience in handling the cans in transportation. The jars cannot move around within the lid, as such movement is prevented by the horizontal partition, and as the cover rests against 95 the tops of the jars the can may be entirely overturned without any breakage or loss of the jars. The cover being sealed to the lid and the can, it cannot be removed without such tampering being detected.

100 The device is very simple and will add but an inconsiderable trifle to the cost of the cans.

Having thus described my invention, what

I claim, and desire to secure by Letters Patent, is—

1. A milk-can lid having a horizontal partition adapted to receive sample-jars, a keeper 5 on the side of the lid, a cover having a tongue engaging the said keeper, the said cover being adapted to rest on the tops of the sample-jars, and means for fastening the cover to the lid.
- 10 2. The combination of the lid adapted to receive sample-jars and having a keeper on its side, a cover having a tongue engaging

said keeper and provided with a fastening-plate at a point removed from the said tongue, a sealing-wire inserted through said fastening-plate and the side of the lid, and a seal holding the ends of the said wire. 15

In testimony whereof I have signed this specification in the presence of two subscribing witnesses.

HARRY E. DILL.
